UNITED STATES PATENT OFFICE.

FRANZ TRINKS, OF BRUNSWICK, GERMANY.

CALCULATING-MACHINE.

1,162,667.

Specification of Letters Patent. Patented Nov. 30, 1915.

Application filed April 26, 1915. Serial No. 24,100.

To all whom it may concern:

Be it known that I, FRANZ TRINKS, manufacturer, citizen of the Duchy of Brunswick, Empire of Germany, residing at 5 Brunswick, Germany, have invented certain new and useful Improvements in Calculating-Machines, of which the following is a specification.

My invention relates to improvements in 10 calculating machines, and more particularly in calculating machines of the class in which revolutions counting mechanism is provided which is equipped with resetting devices, and in which the numeral wheels 15 have two series of numbers arranged around their circumference, the numbers of the said series being displaced from each other. A calculating machine of this class is described in the patent of the United States No. 20 1,088,486 granted to me February 24, 1914. As described in the specification of the said patent the numeral wheels of the revolutions counting mechanism are equipped with pins or noses which coöperate with rocking carrying 25 levers or hammers and are adapted to be brought from the upper to the lower sides of the heads of the said carrying levers or hammers (or vice versa from the lower to the upper sides thereof) by rotating the 30 numeral wheels through an angle of nearly 360 degrees.

The object of the improvements is to provide mechanism which is particularly suitable for imparting the said rotary movement to the numeral wheels.

With this and other objects in view my invention consists in the matters to be described hereinafter and particularly pointed out in the appended claims.

For the purpose of explaining the invention two examples embodying the same have been shown in the accompanying drawings, in which the same letters of reference have been used in all the views to indicate 45 corresponding parts.

In said drawings—Figure 1, is a cross-section of the calculating machine showing the revolutions counting mechanism, Fig. 2, is a side view of the machine showing the 50 parts for operating the resetting mechanism and rotating the numeral wheels through an angle of a little less than 360 degrees. Fig. 3, is a partial plan view of the part of the calculating machine containing the revolutions counting mechanism partly in section and with the cover of the casing removed,

and Fig. 4, is a side view similar to that shown in Fig. 2, and showing a modification of the operating mechanism. Fig. 5 is a partial plan view of the modification 60 shown in Fig. 4.

For the purpose of explaining the invention reference will be had to a calculating machine of the type shown and described in the patent of the United States No. 1,040,059 65 granted to me October 1, 1912. But I wish it to be understood, that my invention is not limited to the use in combination with the class of calculating machine shown in the drawings, and that also in other respects various changes may be made in the general arrangement and construction of the parts of the machine within the gist of my invention. As described in the specification of the said patent, the calculating machine 70 is equipped with setting mechanism adapted to be rotated by means of a machine crank and consisting of setting disks each of which is provided with a plurality of teeth which are adapted to be shifted into or out 75 of operative positions by means of rotary cam disks, the said setting disks being adapted to transmit the values set thereon through transmission wheels to a main registering mechanism which is mounted on a shiftable 80 carriage. Coaxially of the said registering mechanism a revolutions counting mechanism is provided which is adapted to register the number of the revolutions of the machine crank. These parts are known in the 85 art and they have been fully shown in my aforesaid patent and also in my Patent No. 1,088,486. Therefore I deem it not necessary to describe the general construction of the machine more in detail. 95

Referring now more particularly to those parts of the calculating machine to which my invention more particularly relates, the revolutions counting mechanism comprises numeral wheels 1 each of which has two 100 series of numbers printed thereon, which numbers are displaced from each other, as is shown in Fig. 3. Each of the numeral wheels is rigidly connected with a gear wheel 2 having twenty teeth and meshing with an intermediate gear wheel 3. The intermediate gear wheels are adapted to be operated from driving gear wheels which are equipped each with the teeth and are secured to the shaft 6 of the setting mechanism (not 105 shown). For resetting the numeral wheels 1 a shaft 7 is provided which is provided

with a number of teeth 8 coöperating with noses 9 secured to the numeral wheels 1, said teeth and noses providing the resetting members. The shaft 7 is adapted to be 5 shifted in longitudinal direction so as to be brought with its teeth 8 into resetting position relatively to the noses 9 secured to the numeral wheels, as is known in the art.

Apart from the resetting shaft 7 a second 10 resetting shaft 54 is provided which is connected with the resetting shaft 7 by gear wheels 55 and 56 having a ratio of transmission of 1 to 2, so that for each complete rotation of the shaft 7 the shaft 54 performs 15 two complete rotations in the opposite direction. For shifting the shafts 7 and 54 in longitudinal direction and into resetting positions in opposition to the usual springs acting thereon cam sleeves 13 and 57 are 20 provided which coöperate with noses 11 and 65 connected with the shafts 7 and 54 respectively. The cam sleeves 13 and 57 are rotatably mounted and are adapted to be locked as against rotation by means of spring 25 pressed pawls 58 and 59 engaging in notches 57" and 13" made in flanges 13' and 57' respectively, the form of the said pawls and notches being such, that when rotating the shaft 7 in the direction of the arrow shown 30 in Fig. 2 only the sleeve 13 is locked while the sleeve 57 takes part in the rotation, and vice versa. Therefore when turning the shaft 7 by means of a wing nut 10 secured thereto only one of the resetting shafts 7 or 35 54 is shifted in longitudinal direction and into resetting position relatively to the numeral wheels, so that when turning the wing nut 10 only one of the resetting shafts 7 or 54 is thrown into operation.

Apart from the gear wheel 56 gear wheels 40 60 are mounted on the shaft 54, and the said gear wheels 60 are in mesh with the gear wheels 2 connected with the numeral wheels 1. The diameter of the gear wheels 60 is one-half the diameter of the gear wheels 2. The shaft 54 is provided with pins 61 which are adapted to coöperate with noses 60' secured to the gear wheels 60. Normally the 45 said pins and noses are not in positions for resetting engagement with one another, and they are brought into such positions by shifting the shaft 54 in longitudinal direction, as is known in the art. In the present case the said noses and pins are disposed in 50 such a way, that in the normal positions shown in the figures they are displaced relatively to one another a distance corresponding to one tenth of the circumference of the gear wheels 60, when once rotating the 55 shaft 54 from the normal position shown in the figures through an angle of 360 degrees they are carried along only through nine-tenths of the said angle, and when twice rotating the shaft 54 the gear wheels 60 are 60 rotated through an angle of nineteen tenths

of 720 degrees, so that the gear wheels 2 the diameter of which is the double of that of the gear wheels 60 perform only nineteen twentieths of a complete rotation. The reason for thus operating the gear wheels 70 will be explained hereinafter.

To the pawl 58 a stop member 63 is secured which is adapted to be rocked to the left and into coöperation with a stop 64 connected with the resetting shaft 54, when the 75 pawl 58 is rocked to the left by rotating the wing nut 10 in the direction of the arrow y and imparting resetting operation in the opposite direction to the shaft 54. Thereby the stop plate 63 prevents the resetting shaft 80 54 from being shifted backward in longitudinal direction by the spring acting thereon, as would otherwise be the case when the nose 65 of the shaft 54 which performs two revolutions for each revolution of the shaft 7 has 85 completed the first revolution and arrives again in position for engagement with the corresponding notch 66 of the sleeve 57, in which position of the nose 65 the shaft can be shifted in axial direction by the spring 90 acting thereon. When the resetting operation is completed and the shaft 54 has performed two revolutions and the pawl 58 gets again into engagement with the notch 13", the stop plate 63 releases the shaft 54 95 and permits the same to be returned into normal position in which the resetting pins 61 are out of position for engagement with the noses 60'.

The operation of the machine is as follows: In the normal position of the parts shown in the figures the numeral wheels 1 are adapted to perform additions and multiplications, and the zeros of the said numeral wheels which have been indicated in Fig. 3 100 by the letter a are displayed through the peep holes 19, and the pins 42 by means of which carrying takes place are located at the upper sides of the carrying levers or hammers 47. For resetting the numeral 105 wheels after an addition or multiplication has been made the wing nut 10 is turned in the direction of the arrow x. The sleeve 13 is locked as against rotation by the pawl 58, so that the shaft 7 is shifted in longitudinal 110 direction and resetting takes place in the usual way, while the sleeve 57 is not locked by its pawl 59, so that the shaft 54 which is being rotated from the shaft 7 in the opposite direction is not shifted and remains 115 inoperative. If it is desired to set the numeral wheels 1 in such positions that the other zeros are displayed through the peep holes as is necessary for performing subtractions and divisions, the wing nut 10 is 120 rotated in the opposite direction and in the direction of the arrow y shown in Fig. 2. Now the sleeve 13 is not locked by the locking pawl 58 as against rotation, so that the 125 resetting shaft 7 is not shifted into resetting 130

position, while the resetting shaft 54 the sleeve 57 of which is locked by the pawl 59 is made operative. As stated before the shaft 54 performs two rotations, and as the pins 61 and noses 60' are displaced relatively to each other, during the first rotation of the said shaft the wheels 60 are carried along through nine tenths of the circumference, and during the second rotation 10 they are carried along through ten tenths of the circumference. As there is a ratio of transmission of 1 to 2 between the gear wheels 60 and 2 the said revolution through nineteen tenths of the circumference causes 15 the gear wheels 2 to rotate through nineteen twentieths of the circumference, so that instead of the zeros indicated by the letter *a* the zeros indicated by the letter *b* are displayed through the peep holes 19. During 20 this operation the numeral wheels 1 are rotated in the direction of the arrow *y* shown in Fig. 2, and the pins 42 are brought from their positions above the heads 47 into the positions below the said heads. At the 25 end of this rotation the stops 61 and 60' are located exactly in opposition to each other, so that now by each further rotation of the wing nut 10 in the direction of the arrow *y* all the numeral wheels which may have 30 been brought out of their zero positions are carried along by the resetting shaft 54 and the gear wheels 60 thereof and brought into the proper zero or initial positions.

If it is desired to set the other set of zeros 35 into initial position, all that is necessary is to rotate the wing nut 10 in the direction of the arrow *x* shown in Fig. 2, in which case the resetting shaft 7 is operative so as to return the parts into the normal positions shown in the figures.

The example shown in Figs. 4 and 5 is distinguished from the construction shown in Figs. 1 to 3 in this respect, that the resetting shafts 7 and 54 are coupled by gear 45 wheels 67 and 68 of even diameter, so that they perform the same number of rotations. Accordingly, also the gear wheels 60 and 2 have the same diameter. The resetting pins 61 of the shaft 54 and the noses 60' of the 50 wheels 60 must be displaced from each other a distance corresponding to one twentieth of the circumference of the gear wheels when the parts are in the normal positions shown in Fig. 5 for performing additions 55 and multiplications. The parts 63 and 64 which in the construction shown in Figs. 1 to 3 are provided for preventing axial displacement of the shaft 54 are not necessary in construction shown in Fig. 4.

60 I claim herein as my invention:

1. In a calculating machine, the combination with the revolutions counting mechanism, comprising numeral wheels having two series of numbers displaced from each other, 65 of two resetting mechanisms having differ-

ent end or zero positions and coupled with each other for operation in opposite directions and one of them operative only upon operation in one direction and the other one upon operation in the opposite direction and both adapted when being operated to be set respectively in their end or zero positions.

2. In a calculating machine, the combination with the revolutions counting mechanism, comprising numeral wheels having two series of numbers displaced from each other, of two resetting mechanisms and the resetting members having different end or zero positions and coupled with each other for operation in opposite directions and one of them operative only upon operation in one direction and the other one upon operation in the opposite direction, said resetting members of both resetting mechanisms being so disposed relatively to each other that according to the direction of operation of the resetting mechanisms one or the other gets into end or zero position.

3. In a calculating machine, the combination with the revolutions counting mechanism, comprising numeral wheels having two series of numbers displaced from each other, and carrying mechanism controlled by said numeral wheels, of two resetting mechanisms having different end or zero positions and coupled with each other for operation in opposite directions and one of them operative only upon operation in one direction and the other one upon operation in the opposite direction and both adapted when being operated to be set respectively in end or zero positions and to set the numeral wheels relatively to the carrying mechanism for operation thereof upon rotation of the numeral wheels in one or the other direction.

4. In a calculating machine, the combination with the revolutions counting mechanism, comprising numeral wheels having two series of numbers displaced from each other, of two resetting mechanisms having different end or zero positions and disposed one of them coaxially of the numeral wheels and the other one at the side thereof and coupled with each other for operation in opposite directions and one of them operative only upon operation in one direction and the other one upon operation in the opposite direction and both adapted when being operated to be set respectively in their end or zero positions.

5. In a calculating machine, the combination with the revolutions counting mechanism, comprising numeral wheels having two series of numbers displaced from each other, of two resetting mechanisms, one of said resetting mechanisms comprising a longitudinally shiftable resetting shaft disposed coaxially of the numeral wheels and normally inoperative resetting members and the other one a longitudinally shiftable shaft

41
disposed at the side of the numeral wheels, and normally inoperative resetting members operatively connected with the numeral wheels, and means for each of said shafts 5 and operative upon rotation of the shafts in one direction and inoperative upon rotation thereof in the opposite direction for shifting either one of said shafts in longitudinal direction and with its resetting members in 10 setting position, and an operative connection between said shafts for rotating either one of them in the direction for rendering its resetting members operative.

6. In a calculating machine, the combination 15 with the revolutions counting mechanism, comprising numeral wheels having two series of numbers displaced from each other, of two resetting mechanisms, one of said resetting mechanisms comprising a longitudinally 20 shiftable resetting shaft disposed coaxially of the numeral wheels, and normally inoperative resetting members and the other

one a longitudinally shiftable shaft disposed at the side of the numeral wheels, and normally inoperative resetting members operatively 25 connected with the numeral wheels, and cam sleeves one for each of said shafts and each locked as against rotation in one direction and adapted upon rotation of the coöperating shaft in one direction to shift 30 the same longitudinally and with its resetting members into resetting positions, and an operative connection between said shafts for 35 rotating either one of them in the direction for rendering its resetting members operative.

In testimony whereof I have hereunto set my hand in presence of two subscribing witnesses.

FRANZ TRINKS.
